UNITED STATES PATENT OFFICE

95,778

DESIGN FOR A COMBINED KNIFE, NAIL FILE, AND PENCIL CLIP

Per A. Peterson, New York, N. Y.

Application February 25, 1935, Serial No. 55,592

Term of patent 7 years

To all whom it may concern:

Be it known that I, Per A. Peterson, a citizen of the United States, residing at New York city, in the county of New York and State of New York, have invented a new, original, and ornamental Design for Combined Knife, Nail File, and Pencil Clip, of which the following is a specification, reference being had to the accompanying drawing, forming part thereof.

bined knife, nail file and pencil clip, the knife and file being folded within the clip.

Figure 2 is a perspective view showing the same in a reversed position with the file and knife extended and drawn to an enlarged scale.

I claim:

The ornamental design for a combined knife, nail file and pencil clip, as shown and described.

PER A. PETERSON.
